(57) **CLAIM**

The ornamental design for a panel with column bearing components, as shown and described.

DESCRIPTION

FIG. 1 is a top left perspective view for a panel with column bearing components, showing the new design;

FIG. 2 is a bottom right perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is left side elevation view thereof; and,

FIG. 8 is a right side elevation view thereof.

The broken lines of uneven length illustrate the boundary of the claimed design and form no part thereof. The broken lines of even length shown in the drawings illustrate portions of the panel with column bearing components that form no part of the claimed design.

1 Claim, 8 Drawing Sheets
